UNITED STATES PATENT OFFICE

EMMETT R. WOODS, OF CARLISLE, PENNSYLVANIA

COMBINED COLLAR BUTTON AND TIE SUPPORTER

Application filed March 10, 1931. Serial No. 521,553.

This invention relates to a combined collar button and neck-tie supporter.

Among the several objects of the invention is to provide a device of the character described which is easily positioned for use and which when so positioned will properly retain the tie against downward movement and also retain the device in operative position with respect to the collar band and collar.

With these and other objects in view which will more fully appear, the nature of the invention will be more clearly understood by following the description, the appended claims, and the several views illustrated in the accompanying drawings.

In the drawings:—

Figure 1 is a vertical sectional view showing the application of my invention to a shirt, a collar, a neck-tie,

Figure 2 is a perspective view of the device,

Figure 3 is a side elevation partly in section showing another form of the locking section,

Figure 4 is a view similar to Figure 3 but showing a modified form of the locking section,

Figure 5 is a detail sectional view showing the base and the shank, the latter being shown in cross section,

Figure 6 is a side elevation partly in section showing another modified form of my invention in which the locking section is connected to the shank by a sliding pivot,

Figure 7 is a view similar to Figure 6 but showing the locking section in alignment with the shank of the attaching section,

Figure 8 is a side elevation of the construction shown in Figure 7,

Figure 9 is a view similar to Figure 6 but showing a slightly different construction of locking section,

Figure 10 is a view similar to Figure 1 but showing a slightly modified form of my invention for use with bow-ties, and

Figure 11 is a modified form of locking section.

Like reference numerals designate corre-

sponding parts throughout the several figures of the drawings.

Referring to the accompanying drawings, my invention comprises an attaching section A and a locking section B. The attaching section A as shown in Figures 1-5 inclusive, comprises a base 5 and a shank 6 rigidly connected thereto, and is provided with a transverse opening 7. The locking device B, as shown in Figures 1 and 2, comprises a bar 8 which is bent intermediate its ends to form upper and lower shoulders 9 and 10, the upper end of the bar beyond the shoulder 9 terminating in a tie-engaging pin 11, and the bar below the shoulder 10 terminating in a keeper 12 which extends downwardly through the opening of the shank and projects therebelow to retain the collar against working loose. In this form of the invention, the lower shoulder 10 is a stop 70 to thereby limit the downward movement of the locking section B relative to the shank, and the upper shoulder 9 serves not only to support the neck-tie in proper position but 75 also cooperates with said tie to prevent the device from turning and also to prevent the locking section B from moving upwardly relative to the shank and thereby becoming 80 disengaged therefrom. In Figure 1, I have shown the device as applied to a collar band C of a shirt, a collar D and neck-tie E.

In Figure 3 the locking section F is of slightly different form than the section B. In this form F, the section is formed from 85 a bar 13 having a reduced lower end 14 which forms a resultant shoulder 15, the former passing downwardly through the opening 7 of the shank 6 and projecting therebelow, the shoulder 15 cooperating with the 90 shank 6 to limit the downward movement of the section. The upper end of the section, like in Figures 1 and 2, is provided with an offset or lateral shoulder 16 which terminates in an upwardly extending tie-engaging pin 95 17.

In Figure 4, I have illustrated another form of locking section which I have indicated generally by the reference character G and which comprises a bar 18 having re- 100

duced upper and lower end portions 19 and 20 and forming resultant shoulders 21 and 22 respectively. The bar 18 projects above the upper shoulder 21 and terminates in a tie-engaging pin 23. The reduced end 20 extends downwardly through the opening 7 in the shank 6 and functions in the same manner as the depending portions 12 and 14 of the locking sections B and F. The shoulder 21 10 functions in the same manner as the shoulders 9 and 16 of said sections B and F.

In Figures 6-10, I have illustrated a slightly modified form of attaching section which I have designated by the reference 15 character H. In this form, the section includes a base 24 and a shank 25 which is rigid therewith the latter being provided with a transverse opening 26 which is formed by a slot which extends inwardly from the outer 20 end of the shank. Fixed to the shank 25 and extending transversely across the opening or slot 26 is a pivot pin 27 which is rectangular in cross section. The locking section I as shown in Figures 6, 7 and 8, comprises a bar 28 having a key-hole slot 29 formed adjacent its lower end for receiving the pivot pin 27. The upper end of the bar 28 is provided with an upper shoulder 30 which terminates in an upwardly extending tie-engaging pin 31. 30 The locking section I when in its operative position as shown in Figure 6 is maintained against pivotal movement by reason of the walls of the key-hole slot engaging the opposite faces of the pin. When, however, it is 35 desired to insert the device, the section I is elevated so as to position the enlarged portion of the key-hole slot in registry with the pin 27 and the locking section is then turned to the position shown in Figure 7. The locking section is then moved toward the base 24 in a straight line thereby re-engaging the side walls of the key-hole slot with the opposite faces of the pin 27 to thereby retain 40 the locking section in alignment with the shank 25. After the device has been inserted through the buttonholes of the shirt band and collar, the locking section I is restored to its 45 operative position as shown in Figure 6.

In Figure 9, I have illustrated a slightly 50 modified form of locking section and have designated the same by the reference character J. In this form, the bar 32 is provided with a reduced upper end 33 which terminates in a tie-engaging pin 34, the reduced end 55 forming a resultant upper stop shoulder 35.

In Figure 10, I have illustrated a slightly modified form of locking section which is especially adapted for use with a bow-tie K. In this form, I have designated the locking 60 section by the reference character L. This section comprises a bar 36 which terminates at its upper end in a pin 37 which is bent forwardly or in a direction away from the base 24.

65 In Figure 11, I have shown a further modi-

fied form of locking section. This section is designated by the reference character M and includes a bar 38 having a T-head 39 which terminates in upwardly extending tie-engaging pins 40, 40. The bar intermediate the head 39 and the lower end thereof is provided with a stop shoulder 41. The T-head 39 constitutes the upper stop shoulder.

From the foregoing, it will be observed that I have provided a combined collar button and neck-tie supporter which may be readily applied and which when so applied will securely retain the tie in proper position relative to the collar and which will also cooperate with the tie to retain the same against 75 displacement.

It is of course to be understood that the details of structure and arrangements of parts may be variously changed and modified without departing from the spirit and 80 scope of my invention.

I claim:—

1. In a combined collar button and neck-tie supporter, the combination of an attaching section comprising a base and a shank 85 rigidly connected thereto, the latter being provided with a transverse opening, and a locking section comprising a bar movably fitted transversely in the opening and extending above and below the shank, the upper end of the bar being provided with a tie-engaging pin.

2. In a combined collar button and neck-tie supporter, the combination of an attaching section comprising a base and a shank rigidly connected thereto, the latter being provided with a transverse opening, and a locking section comprising a bar movably fitted transversely in the opening and extending above and below the shank, the upper end of the bar being provided with a tie-engaging pin and with a stop shoulder intermediate the shank and the pin.

3. In a combined collar button and neck-tie supporter, the combination of an attaching section comprising a base and a shank rigidly connected thereto, the latter being provided with a transverse opening, and a locking section comprising a bar movably fitted transversely in the opening and having reduced ends forming resultant shoulders, the lower shoulder engaging the shank to limit the downward movement of the bar relative to the shank and the lower end of the bar projecting below the shank, the upper end of the shank being formed into a tie-engaging pin.

4. In a combined collar button and neck-tie supporter, the combination of an attaching section comprising a base and a shank rigidly connected thereto, the latter being provided with a transverse opening, and a locking section comprising a bar movably fitted transversely in the opening and extending above and below the shank, the upper end of the

bar being provided with a tie-engaging pin, the bar intermediate its lower end and the pin being provided with upper and lower stop shoulders for respectively limiting the downward movement of the tie and bar relative to the shank.

5. In a combined collar button and neck-tie supporter, the combination of an attaching section comprising a base and a shank rigidly connected thereto, the latter being provided with a transverse opening, and a locking section comprising a bar movably fitted transversely in the opening and extending above and below the shank, the upper end of the 10 bar being provided with a tie-engaging pin, the bar intermediate its lower end and the pin being bent in opposite directions to form upper and lower stop shoulders for respectively limiting the downward movement of the tie and bar relative to the shank.

15. In a combined collar button and neck-tie supporter, the combination of an attaching section comprising a base and a shank rigidly connected thereto, the latter being provided with a transverse opening, and a locking section comprising a bar mounted in the opening of the shank and having a sliding pivotal connection therewith comprising a stationary pivot pin of angular cross section extending 20 across a key hole slot in the bar whereby the bar in one position may be alined with the shank and in another position retained in a transverse plane relative to the shank with the lower end of the bar disposed below the shank, 25 the upper end of the shank being provided with a tie-engaging pin.

30. In a combined collar button and neck-tie supporter, the combination of an attaching section comprising a base and a shank rigidly connected thereto, the latter being provided with a transverse opening, and a locking section comprising a bar mounted in the opening of the shank and having a sliding pivotal connection therewith comprising a stationary 35 pivot pin of angular cross section extending across a key-hole slot in the bar whereby the bar in one position may be alined with the shank and in another position retained in a transverse plane relative to the shank with 40 the lower end of the bar disposed below the shank, the upper end of the shank being provided with a tie-engaging pin and with a tie-supporting shoulder intermediate the pin and shank.

45. In testimony whereof I hereunto affix my signature.

EMMETT R. WOODS.
